UNITED STATES PATENT OFFICE.

GUSTAV DIETERT, OF KERRVILLE, TEXAS.

WINDMILL.

SPECIFICATION forming part of Letters Patent No. 400,195, dated March 26, 1889.

Application filed May 31, 1888. Serial No. 275,567. (Model.)

To all whom it may concern:

Be it known that I, GUSTAV DIETERT, a citizen of the United States, residing at Kerrville, Kerr county, Texas, have invented certain new and useful Improvements in Windmills, of which the following is a full specification.

My improvements are designed more particularly for use in connection with that class of wind-motors known as "the vertical wheel;" and the said improvements consist in certain features of novelty, which will now be described, with reference to the accompanying drawings, and then more specifically pointed out in the claims hereto annexed.

In said drawings, Figure I is a side elevation of a windmill, showing a portion of the wheel and also a portion of the tail, and the trellis-work or tower omitted. Fig. I^a is a detail view of the ball-and-socket joint hereinafter referred to. Fig. I^b is a sectional view taken on the line b b, Fig. I^a. Fig. II is a plan view of the same. Fig. III is a detail view, partly in vertical section, showing the crown of the tower with the wheel-support fitted thereon, portions broken away. Fig. IV is a detail view looking in the direction of the arrow in Fig. II, the arms for supporting the wheel being broken away.

1 represents a portion of the wind-wheel upon the shaft 2, which latter is journalled in suitable bearings or boxes, 3, carried by the two arms 4. These arms are preferably cast integral with the sleeve or collar 5, which, together with said arms, forms the wheel-support.

6 is the part which will be hereinafter designated the "crown" of the tower, which may be secured in any suitable manner to the top of the trellis-work of which the tower is formed. Projecting upwardly and axially from this crown 6 is a tenon or journal, 7, around which the collar or sleeve 5 is adapted to revolve, the latter resting upon a shoulder or flange, 8, on said crown. Formed around this tenon is a peripheral groove or channel, 9, in which engages a set-screw or pin, 10, driven through the collar or sleeve 5 for preventing the latter from being lifted vertically from said tenon, but at the same time permitting its free revolution thereon. Passing vertically through the tenon and

crown 6 is a hollow shaft, 11, which at its lower end is suitably stepped in a bearing or step, (not shown,) and at its upper end is provided with a beveled gear, 12, adapted to be engaged by a similar gear, 13, mounted upon the wheel-shaft 2.

The tail or rudder 14 is provided with a stem, 15, which latter is planted in a stock or socket, 16, hinged to an arm, 17, the latter being secured to or made integral with the collar or sleeve 5, or with one of the arms 4, as shown in dotted lines in Fig. I. These two parts, 16 and 17, are hinged together by means of a ball-and-socket joint of the usual and well-known construction, the arm 17 bearing the ball 18, while the stock 16 carries the socket 19, the latter being made in two sections, as shown in dotted lines in Fig. I and in full lines in Figs. I^a I^b, and provided with a lateral groove, 21^a, for the passage of the arm 17 as the rudder turns, and the lower section being provided with a vertical notch or groove, 20, in order to permit the tail or rudder to be folded downward in a vertical position when the same is to be removed or when it is desired to have the mill remain inoperative. Secured around this stem 15 is a ring or collar, 21, which is provided at both sides with rings 22 for the attachment of cords 23 24, the former passing around the pulley 25, which is mounted in an approximately horizontal position in the recessed end of an arm, 26, and thence over a pulley, 27, which is mounted vertically and directly over the hollow shaft 11 in the bifurcated end of the arm 28. The cord after passing over this latter pulley descends through the hollow shaft within the reach of the operator, whereby he may be enabled by drawing upon said cord to pull the tail or rudder toward the wind, and consequently throw the wind-wheel out of the wind or with its edge toward the same. The arms 26 and 28 are preferably made integral with a bracket, 29, secured by any suitable means to the side of the collar or sleeve 5.

The tail is maintained in the wind by means of a weight, 30, which is mounted upon one arm of an angle-lever, 31, and held at any desired position on said arm by means of a set-screw, 32, it being prevented from slipping from said arm by an ordinary stop or pin, 33,

inserted through the end of the latter. The other arm of this angle-lever is connected by means of the cord 24 to the other of said rings 22, and the lever is pivoted by means of a bolt, 34, to a plate, 35. This plate is preferably cast integral with two converging arms, 36, which form a bracket, they being secured at their diverging ends to the revoluble sleeve or collar 5 by means of the bolts 37, as shown.

10 By the construction thus described it will be seen that the weight 30 may be placed upon the angle-lever to hold the tail to the wind as long as the latter remains at a certain velocity; but when the velocity increases the 15 weight 30 will be overcome and the wheel and tail or rudder will change position relative to one another.

In order that I may regulate the angle of the wind-wheel to the wind, I provide the stock 20 or socket 16 with an outwardly-projecting arm, 38, which it is preferable to make integral with the stock, and which is provided at its inner end with the long set-screw 39. The end of this set-screw is adapted to abut 25 against the side of the arm 4 when the wind decreases and the weight 30 returns the rudder to its normal position, and it will be seen that by adjusting this screw the normal position of the rudder relatively to the wind- 30 wheel may be varied to a considerable degree, and thus prevent the wheel from turning broadside to the wind whenever the pressure of the latter becomes less than that of the weight 30. The tail is prevented from tak- 35 ing a downward turn by means of a stay-rod, 40, which is secured to a hook, 41, on the yoke

or brace 42, that projects from one journal box or bearing to the other over the wheel 13, and thus braces the arms 4, and this rod is secured at its lower end to an arm, 43, which 40 is preferably made integral with the ring or collar 21 on the stem 15. The purpose of this arm 43 is to prevent the rudder revolving transversely to a horizontal position, as it is readily seen that if the rod 40 were attached 45 directly to the stem, or even to a link in the collar thereon, the leverage would not be sufficient to keep the stock in which the rudder is mounted from revolving on the ball of the joint. 50

Having thus described my invention, what I claim as new therein, and desire to secure by Letters Patent, is—

1. The combination, with the revoluble wheel-support, having the yoke 42, and the 55 tail or rudder having a stem, of a ball-and-socket joint, by which said stem is secured to said wheel-support, a collar or ring, 21, on said stem, and a rigid arm projecting upwardly from said ring and connected with said yoke, 60 substantially as set forth.

2. In a windmill, the combination, with the stem 15, the collar 5, the arm 17, secured thereto, and the ball 18 on said arm, of the stock 16, receiving said stem, the socket 19, 65 made integral with stock 16, receiving said ball, and the arm 38, made integral with said stock and carrying a set-screw, as set forth.

GUSTAV DIETERT.
